UNITED STATES PATENT OFFICE

132,626

DESIGN FOR A SEWING MACHINE FRAME

Malcolm S. Park, Mount Kisco, N. Y., assignor to
The Singer Manufacturing Company, Eliza-
beth, N. J., a corporation of New Jersey

Application April 18, 1942, Serial No. 106,616

Term of patent 14 years

To all whom it may concern:

Be it known that I, Malcolm S. Park, a citizen of the United States, residing at Mount Kisco, in the county of Westchester and State of New York, have invented a new, original, and ornamental Design for a Sewing Machine Frame, of which the following is a specification, reference being had to the accompanying drawing, forming a part thereof.

Fig. 1 is a front perspective view of a sewing machine frame showing my new design.

Fig. 2 is a rear perspective of the sewing machine frame shown in Fig. 1.

I claim:

The ornamental design for a sewing machine frame, as shown.

MALCOLM S. PARK.
